UNITED STATES PATENT OFFICE.

ALBERT G. CLASS, OF CLEVELAND, OHIO, ASSIGNOR OF ONE-HALF OF HIS
RIGHT TO KIRKE D. BISHOP, OF SAME PLACE.

DRAIN-FAUCET.

SPECIFICATION forming part of Letters Patent No. 224,582, dated February 17, 1880.

Application filed July 28, 1879.

To all whom it may concern:

Be it known that I, ALBERT G. CLASS, of Cleveland, in the county of Cuyahoga and State of Ohio, have invented a certain new and Improved Drain-Faucet; and I do hereby declare that the following is a full, clear, and complete description thereof.

The nature of this invention relates to an improvement in faucets for drawing liquids from barrels.

Said improvement consists of attaching to the inner end of the stem of the faucet a flexible tube in such way that when the implement is inserted in the draft-hole of the barrel the flexible tube will be sprung or turned downward, so that the extreme end thereof will be at or near the bottom of the vessel—that is to say, below the opening of the faucet—so that all, or nearly all, the liquid below the opening of the faucet can be drawn off, which is left in the barrel when an ordinary faucet is used for draft.

A full detailed description of the improvement and the operation of the same are as follows, reference being had to the accompanying drawings, making a part of this specification, in which—

Figure 1 is a side view of the faucet having attached thereto the aforesaid improvement. Fig. 2 is a sectional detached section. Fig. 3 is an end view of the faucet attachment. Fig. 4 is a side view of the tubular attachment of the faucet turned upward in position for being inserted in the barrel.

Like letters of reference refer to like parts in the several views.

It is well known that the contents of a barrel are usually drawn from the head by means of a faucet inserted therein near the bottom as the barrel lies upon its side. In consequence of the bilge of the barrel, and also for the reason that the hole for the faucet is made a little above the chine, all the liquid above the faucet will flow therefrom, but that which remains below will not run off unless the barrel be tilted for that purpose.

The faucet above alluded to is or may be of the ordinary construction, consisting, in brief, of the stem or body A, Fig. 1, and the key B. To the barrel end of the faucet or stem is se-

cured, by any suitable means, a plug, C. That part screwed into the stem is provided with an opening corresponding to the base of the stem, and therein is inserted a piece of rubber tubing, D, which, as will be seen in the drawings, projects downward from the end of the faucet. This downward direction of the tube is caused by a bar, a, extending across the outer end of the plug between the cheeks b and c, under which the tube projects, as shown in Figs. 2 and 3.

It will be obvious that when the end of the faucet is inserted in the barrel the end of the tube will descend below the outlet or bore of the faucet, the tubing being sufficiently long to reach to the bottom of the cask and rest thereon upon the corner d, leaving the end of the tube open for the liquor to pass in. The tube, as will be seen, is cut diagonally across for that purpose.

Some liquors—as beer, for instance—are drawn from the casks while under pressure; hence as long as the contents of the barrel are above the opening of the faucet no trouble is found in drawing said contents; but when the liquor falls below the bore of the faucet it ceases to run—that is, when an ordinary faucet is used—whereas, by having the tubular attachment applied to the faucet, as herein described, all the liquor, or nearly all, that may be below the bore of the faucet will be drawn off, it being forced out by the applied pressure.

In the event the barrel is tipped up the liquor therein will flow out without the application thereto of pressure exerted by mechanical means when the liquor is below the bore of the inner end of the faucet, but above the outer end, for the reason that the tube attached to the inner end of the faucet, as above described, converts the faucet into a siphon, which, by siphonic action, will draw off the liquor remaining in the cask.

To insert the end of the faucet in the barrel the tube D is turned up over the bar a of the plug and back between the sides or cheeks b and c, as shown in Fig. 4. In this position of the tube it takes up no more room than the thickness of the plug. Therefore it can be easily thrust into the draft-hole made in the barrel.

When the end of the faucet is projected into the cask the rubber tube will spring to the position shown in Fig. 1; extending down into the liquor below the faucet, as and for the purpose 5 aforesaid.

What I claim as my invention, and desire to secure by Letters Patent, is—

In a faucet for drawing liquors from barrels, a hollow plug, C, attached to the inner end of 10 the stem of said faucet, and having inserted

therein a flexible tube deflected downward by a bar, a, across the outer end of the plug between the sides or cheeks b c, under which bar the said tube passes, for the purpose specified, and substantially as described.

ALBERT G. CLASS.
